(57) **CLAIM**

The ornamental design for valve carousel, as shown.

DESCRIPTION

FIG. 1 is a front right perspective view of the carousel of the valve carousel showing my new design;

FIG. 2 is a rear right perspective view thereof;

FIG. 3 is a front left perspective view thereof;

FIG. 4 is a rear left perspective view thereof;

FIG. 5 is a right elevation view thereof;

FIG. 6 is a left elevation view thereof;

FIG. 7 is a front elevation view thereof;

FIG. 8 is a rear elevation view thereof;

FIG. 9 is a top plan view thereof;

FIG. 10 is a bottom plan view thereof;

FIG. 11 is a front right perspective view of the carousel cap of the valve carousel showing my new design;

FIG. 12 is a rear right perspective view thereof;

FIG. 13 is a front left perspective view thereof;

FIG. 14 is a rear left perspective view thereof;

FIG. 15 is a right elevation view thereof;

FIG. 16 is a left elevation view thereof;

FIG. 17 is a front elevation view thereof;

FIG. 18 is a rear elevation view thereof;

FIG. 19 is a top plan view thereof;

FIG. 20 is a bottom plan view thereof;

FIG. 21 is a front right perspective exploded view of the valve carousel in an unassembled state showing my new design;

FIG. 22 is a front right perspective view of the valve carousel in an assembled state;

FIG. 23 is a front right perspective exploded view of the unassembled valve carousel as part of an unassembled serviceable valve carousel system showing an environment of use;

FIG. 24 is a front right perspective exploded view of an assembled valve carousel as part of the partially unassembled serviceable valve carousel system showing an environment of use;

(Continued)

FIG. 25 is a front right perspective view of the assembled valve carousel as part of the assembled serviceable valve carousel system showing an environment of use; FIG. 26 is a rear right perspective view of the assembled valve carousel as part of the assembled serviceable valve carousel system showing an environment of use; and, FIG. 27 shows a right elevation view of the valve carousel as part of a serviceable valve carousel system installed in a marine sanitation system showing an environment of use. The broken lines in the figures show portions of the valve carousel, or environmental structure, which form no part of the claimed design.

1 Claim, 14 Drawing Sheets
